UNITED STATES PATENT OFFICE.

WILLIAM S. DOLBEY, OF BROOKLYN, NEW YORK.

DESIGN FOR CAPITAL LETTERS.

SPECIFICATION forming part of Design No. 14,181, dated August 21, 1883.

Application filed July 2, 1883. Term of patent 7 years.

To all whom it may concern:

Be it known that I, WILLIAM S. DOLBEY, a citizen of the United States, residing at Brooklyn, in the county of Kings and State of New York, have invented and produced a new and original Design for Capital Letters, of which the following is a specification, reference being had to the accompanying drawing, forming a part thereof.

10 The drawing shows a complete alphabet of capitals made in accordance with my invention, the object of my design being to produce a new and original alphabet of capitals, wherein each letter is designed with a view to 15 its occupying substantially the same space,

and at the same time presenting the same general relative outline, so that, for example, the letter I, usually a narrow letter, will fill as much space as any other letter, while the M or the W, broad letters, will occupy no more. 20

What I claim is—

The design for capital letters shown and described.

In testimony that I claim the foregoing I have hereunto set my hand in the presence of two 25 witnesses.

WILLIAM S. DOLBEY.

Witnesses:

A. M. PIERCE,
WM. A. LOWE.
